FURNACE

Pius P. De Witt, St. Louis County, Mo.

Application June 17, 1940, Serial No. 340,975

14 Claims. (Cl. 126—147)

This invention relates to furnaces and more particularly to devices adapted to be installed in coal burning furnaces to effect economy of fuel and elimination of smoke.

It has for its principal objects to provide a device for coal burning furnaces, stoves or the like which will insure complete combustion of the coal, including the burning of volatiles, thereby eliminating or lessening materially smoke, and which will reduce fuel consumption by providing more heat per unit of fuel burned. Further objects are to provide a device which is simple in construction, inexpensive to manufacture and efficient in operation and which may be easily and quickly installed in any ordinary coal burning furnace, stove or the like.

The invention consists principally in providing the fire pot of the furnace with a central partition which terminates short of the bottom thereof and in providing a movable cover member adapted to selectively cover either side of the divided fire pot. It further consists in the furnace and in the parts and combinations and arrangements of parts hereinafter described and claimed.

In the accompanying drawings wherein like reference numerals refer to like parts wherever they occur,

Fig. 1 is a front elevation of a furnace embodying my invention,

Fig. 2 is a vertical sectional view of the furnace showing the cover member covering one side of the fire pot of the furnace,

Fig. 3 is a view similar to Fig. 2 showing the cover member over the opposite side of the fire pot,

Fig. 4 is a sectional view taken on the line 4—4 in Fig. 2,

Fig. 5 is a view taken on the line 5—5 in Fig. 2,

Fig. 6 is a perspective view of the partition for dividing the fire pot,

Fig. 7 is a vertical sectional view of a modification of my invention,

Fig. 8 is a view taken on the line 8—8 in Fig. 7,

Fig. 9 is a view taken on the line 9—9 in Fig. 8,

Fig. 10 is a sectional view similar to Figs. 4 and 8 of another modification of my invention,

Fig. 11 is a view taken on the line 11—11 in Fig. 10; and

Fig. 12 is a vertical sectional view of another modification of my invention showing a cover member which is hinged to the fire pot partition.

The construction illustrated in the drawings is an ordinary furnace construction and includes the furnace walls 1, the usual fire door 2 which

provides access to the inside of the furnace to permit the charging of the furnace with coal or the entry of firing tools for stoking and raking the fire, and the usual ash pit door 3 in the lower portion of the furnace which provides access to the ash pit to permit the removal of ashes. The inside of the furnace is provided with the usual fire pot 4 whose sides taper toward the grate 5.

10 The fire pot is provided with a central partition 6 of fire brick or other suitable material having tapering ends which abut against the sloping walls of the fire pot to hold the partition in position. Said partition extends diametrically across the upper portion of the fire pot and divides it into two combustion chambers 7. The partition is of less height than the fire pot and does not extend to the bottom thereof but terminates a short distance from the grate 5, forming an opening 8a which extends diametrically across the fire pot and connects the lower portions of said chambers 7. Small openings 8 extending through the partition also form passageways which communicate with the two chambers and together with the opening 8a permit the volatile matter from one chamber to pass into the other. If desirable, these openings 8 may be eliminated. The top of the partition is provided with a saddle member 9 which is preferably a separate member made of cast iron but may be made of any other suitable material or, if desirable, may be formed integral with said partition. There is a groove 10 in the saddle member extending longitudinally thereacross and the ends of said saddle member have notches 11 therein. The middle portion of said groove is provided with an upstanding pin 10a which projects above the top of the saddle member.

Two semi-circular flanges 12, the ends of which terminate adjacent to the saddle member, extend inwardly from the upper portion of the fire pot and are preferably integral therewith. Upwardly extending marginal flanges 13 on these flanges 12 form grooves 14. The notches 11 in the ends of the saddle member and the grooves 14 form a continuous annular groove around the upper portion of the fire pot.

50 A semi-circular cover member 15 of cast iron or other suitable material is provided which is one-half the size of the fire pot and which is adapted to selectively cover either one of the chambers 7 formed by the partition. The diameter of said cover member is provided with a downwardly extending wedge-shaped rib 16, said rib being adapted to rest in the saddle groove

10. A recess 16a is provided in the middle of the rib 16 and in the adjacent portion of the cover for retaining the pin 10a projecting from the saddle member. The rib 16 on the cover and the groove 10 in the saddle serve as a means of locating the cover in either of its two proper positions and also serve to seal the covered chamber against the escape of volatile matter from the coal. The pin 10a and the recess 16a serve as a means of pivoting the cover from side to side. A downwardly extending semi-circular flange 17 on the cover member is adapted to rest in the grooves 14 formed by the fire pot flanges 12 and their marginal flanges 13 and to prevent the escape of gas from the covered chamber and also serve as a guide for revolving the cover from one chamber to the other. The top of the cover has a series of upstanding radiating ribs 18. Some of these ribs are provided with upstanding lugs 19 having openings 20 therethrough, said lugs serving as a means for revolving the cover from the top of one chamber to the other.

In the operation of the hereinbefore described device, one of the chambers 7 is filled with fuel as for example, bituminous coal. This filled chamber is covered with the cover member 15, the other chamber being open. The downwardly extending diametrical rib 16 of the cover rests in the saddle groove to properly locate the cover over the chamber filled with coal. A fire is started in the open combustion chamber and the heat from this fire drives the volatile matter from the bituminous coal in the covered chamber, thereby forming coke or semi-coke in said chamber. The volatile matter driven off in this chamber cannot escape upwardly into the air so it must pass under the partition or through the openings 8 in the partition into the uncovered combustion chamber where it passes through the hot coals and the fire where it is completely consumed. After the coal in the uncovered side has burned down, fresh coal is added to fill the chamber and the cover is revolved around the fire pot groove by a rod engaging one of the lugs thereon until it completely covers the newly charged chamber and the rib rests in the saddle member groove. The pin 10a extending from the saddle member 9 and the recess 16a in the cover serve as a means of pivoting the cover from side to side. The bottom of the covered chamber will always have some combustion due to a small amount of air coming from the grate and passing through the coal toward the vent holes 8 in the partition. Consequently, the coked side which is uncovered by revolving the cover to the newly filled side will then be ignited by the small fire at the bottom thereof. This coked fuel will burn free from smoke and the coal of the other side will have the volatile matter driven off in the same manner as above described and thus form coke. When the cover is again revolved, the coke will be ignited by the fire burning in the bottom of its combustion chamber. It is noted that the volatile released from the coal in the covered side cannot pass through the cover member but must always pass into the burning side where it is consumed.

The modification shown in Figs. 7, 8 and 9 is similar to the construction described above. However, in this modification, a partition 21 having a curved bottom is shown. This curved bottom increases the size of the opening 22 between the bottom of the partition and the grate 23. This construction also shows a fire pot flange 24 separate from the fire pot 25, said rib being 75

secured to the fire pot by bolts 26. This construction or any other suitable means of fastening the fire pot flange to the fire pot may be used with existing furnaces. It is noted that in this modification, the partition does not have the small openings 8 which extend through the partition and also this modification does not have the pin 10a in the saddle member and the recess 16a in the cover member, both of which may be eliminated in any of the constructions if desirable.

The construction illustrated in Figs. 10 and 11 is also similar to the hereinbefore described construction. However, the construction illustrated in these figures shows a furnace having a fire pot 27 of fire brick. As shown, the partition 28 is set in recesses 29 in the fire brick. An annular metal member 31a is mounted on top of the fire bricks and the cover member 30 rests in a groove 30a in the annular metal member on top of the fire bricks and on the partition.

The modification illustrated in Fig. 12 shows a square furnace having a cast iron cover 31 which is pivotally secured to a saddle member 32 seated on top of the central partition 33 in the middle of the fire pot. A bolt 34 extends through the saddle member and partition to secure the saddle member to the partition, thereby retaining the saddle member in place. Ribs 35 extending inwardly from the fire pot provide rests for the cover member and lugs 36 on either side of the cover having openings 37 therethrough provide means whereby the cover may be swung from one side of the furnace to the other.

The advantages of my construction are numerous. My device is inexpensive to construct and to install and may be used in almost all types of coal burning furnaces, stoves or the like with but few alterations being necessary. My device is simple to operate and can be used to burn all sizes of coal. Not only does it eliminate smoke by burning the volatile matter in the coal but all of the volatile is also consumed without the use of a forced draft, thus, fly ash is eliminated as it is not forced into the chimney by a forced draft.

Obviously, numerous modifications may be made and I do not wish to be limited to the precise construction shown.

What I claim is:

1. A furnace comprising a fire pot in the lower portion thereof, a partition for said fire pot, the upper portion of said partition terminating adjacent to the top of said fire pot and the lower portion of said partition terminating at a level above the bottom of said fire pot and forming chambers connected by an opening beneath said partition and above the bottom of the fire pot, and a movable cover for selectively covering either of said chambers and cutting off communication between fuel in the closed chamber and the space above said fire pot.

2. A furnace comprising a fire pot, a partition for said fire pot forming two combustion chambers, said partition terminating adjacent to the top of said fire pot, a passageway adjacent to the bottom of said fire pot connecting said chambers, openings through said partition, a movable cover member adapted to selectively cover either of said chambers, and a flange extending inwardly from said fire pot to provide a rest for said cover.

3. A furnace comprising a fire pot, a partition of fire brick for said fire pot, said partition having small openings therethrough and extending

from the top to a level above the bottom of said fire pot to form combustion chambers connected by an opening beneath said partition and above the bottom of said fire pot, a movable cover for selectively covering either of said chambers, said cover having a downwardly extending flange, and a grooved flange extending inwardly from said fire pot for receiving said cover flange.

4. A furnace comprising a fire pot, a partition for said fire pot, said partition having small openings therethrough and extending only part way to the bottom of said fire pot to form combustion chambers connected by an opening beneath said partition and above the bottom of said fire pot, a movable cover for selectively covering either of said chambers, a flange extending inwardly from said fire pot for supporting said cover and means on said cover whereby said cover may be moved from one chamber to the other.

5. A furnace comprising a fire pot, a partition member in the central portion of the fire pot extending part way to the bottom thereof to form connected chambers, the ends of said partition abutting against said fire pot and said partition having small openings therethrough, the top of said partition having a longitudinal groove therein, grooved flanges extending inwardly from the upper portion of said fire pot, and a movable cover member for selectively covering either of said chambers having a downwardly extending rib adapted to be retained in said partition groove, and a downwardly extending cover flange adapted to be retained in said groove fire pot flanges.

6. A furnace comprising a fire pot, a partition member in the central portion of the fire pot extending part way to the bottom thereof to form two connected chambers, the ends of said partition abutting against said fire pot and said partition having small openings extending therethrough a longitudinally grooved saddle member on the top of said partition, grooved flanges extending inwardly from the upper portion of said fire pot, and a movable cover member for selectively covering either of said chambers having a downwardly extending rib adapted to be retained in said saddle groove, and a downwardly extending cover projection adapted to be retained in said grooved fire pot flanges.

7. A furnace comprising an annular fire pot, a partition member in the central portion of the fire pot extending part way to the bottom thereof to form two connected chambers, the ends of said partition abutting against said fire pot and said partition having small openings extending therethrough, a longitudinally grooved saddle member on the top of said partition, grooved flanges extending inwardly from the upper portion of said fire pot, and a movable semi-circular cover member for selectively covering either of said chambers having a downwardly extending rib adapted to be retained in said saddle groove, a downwardly extending cover flange adapted to be retained in said grooved fire pot flanges, and means on said cover whereby said cover may be moved from one chamber to the other.

8. A furnace comprising a fire pot, a partition member in the central portion of the fire pot extending from the top to a level above the bottom of the fire pot to form two chambers connected by an opening beneath said partition and above the bottom of the fire pot, the ends of said partition abutting against said fire pot, said partition having small openings extending there-

through, a longitudinally grooved saddle member on the top of said partition, an upstanding pin projecting from the middle portion of said groove, said member having notches at the ends thereof, grooved flanges extending inwardly from the upper portion of said fire pot, and a movable cover member for selectively covering either of said chambers having a downwardly extending diametrical rib adapted to be retained in said saddle groove, a recess in the middle of said rib extending through said cover member for receiving said pin, a downwardly extending cover flange adapted to be retained in said grooved fire pot flanges, and said cover member having upstanding lugs with openings therethrough whereby said cover may be moved from one chamber to the other.

9. A furnace comprising a fire pot of fire brick, a grooved annular member mounted on top of said fire pot, a partition for said fire pot, said partition having small openings therethrough and terminating short of the bottom of said fire pot to form connected combustion chambers, a movable cover for selectively covering either of said chambers, said cover resting on said partition and on said annular member, and means on said cover whereby said cover may be moved from one chamber to the other.

10. A furnace comprising an annular fire pot, a partition for said fire pot forming two combustion chambers, said partition terminating adjacent to the top of said fire pot, a passageway adjacent to the bottom of said fire pot connecting said chambers and a cover member whose inner end is pivotally mounted on said partition, said cover member being adapted to cover either of said chambers.

11. A furnace comprising a fire pot, a partition member in the central portion of the fire pot extending part way to the bottom thereof to form two chambers connected by an opening beneath said partition and above the bottom of the fire pot, the ends of said partition abutting against said fire pot and said partition having small openings extending therethrough, a saddle member on the top of said partition, ribs extending inwardly from the upper portion of said fire pot, a cover member for selectively covering either of said chambers, the inner end of said cover member being pivotally mounted on said saddle member, ribs extending inwardly from said fire pot wall to provide a rest for said cover and lugs on the top and bottom of said cover member whereby said cover may be swung from one chamber to the other.

12. A furnace attachment comprising a partition member adapted to be placed in the central portion of the fire pot of a furnace and extend to a level adjacent to the top of said fire pot, the lower portion of said partition being adapted to extend only part way to the bottom of said fire pot, said partition having openings therethrough, and a cover member adapted to selectively cover either half of the furnace fire pot divided by said partition.

13. A furnace attachment comprising a partition member adapted to be placed in the central portion of the fire pot of a furnace and to terminate short of the bottom thereof, said partition having small openings therethrough, a grooved saddle member on top of said partition, and a cover member adapted to selectively cover either half of the furnace fire pot divided by said partition, said cover having a downwardly extending rib adapted to rest in said saddle groove.

14. A furnace attachment comprising a partition member adapted to be placed in the central portion of the fire pot of a furnace and to terminate short of the bottom thereof, said partition having small openings therethrough, a 5 grooved saddle member on top of said partition, grooved flanges adapted to be secured to the upper portion of the furnace fire pot and a cover

member adapted to selectively cover either half of the furnace fire pot divided by said partition, said cover having a downwardly extending rib adapted to rest in said saddle groove and a downwardly extending flange adapted to rest in the grooves of said fire pot flanges.

PIUS P. DE WITT.
